UNITED STATES PATENT OFFICE.

IVAN L. MELOON AND PHINEAS S. WHITING, OF LIMA, OHIO; SAID WHITING
ASSIGNOR OF ONE-HALF HIS RIGHT TO ALEXANDER L. RICHMOND, OF
SAME PLACE.

DEVICE FOR AUTOMATICALLY STOPPING TRAINS.

SPECIFICATION forming part of Letters Patent No. 395,163, dated December 25, 1888.

Application filed January 14, 1888. Serial No. 260,792. (No model.)

To all whom it may concern:

Be it known that we, IVAN L. MELOON and PHINEAS S. WHITING, citizens of the United States, and residents of Lima, in the county 5 of Allen and State of Ohio, have invented a new and useful Device for Automatically Stopping Trains, of which the following is a specification.

Our invention relates to an improved device for stopping railway-trains and preventing them from running into open switches unawares; and it consists, principally, of a device set at the side of the track that operates in connection with a lever on the train to set 15 the air-brakes and stop the train before reaching the switch.

The device is intended to operate with either the straight or automatic air-brake, and can also be used as a block at any station.

20 Figure 1 is a side view; Fig. 2, a top view, with cover removed; Fig. 3, top view of cover; Fig. 4, top detail view, with part of the solenoid removed to show the rack and dogs; Fig. 5, a side view of the tender and attachment; Fig. 25 6, end view of the same; Fig. 7, top view of track-switch, wires, &c.; Fig. 8, side view of switch-throwing device and connections; Fig. 9, bearing for post or standard A; Fig. 10, side detail view of same; Fig. 11, front view of bar 30 or rack C; Fig. 12, end view of solenoid, bar C, and anti-friction rolls; Fig. 13, top detail view of part of switch-standard and contact-springs.

The construction and operation of our device are as follows:

Along side of the track, a quarter or a half mile from the switch, as desired, is a box about fifteen inches by eight inches, and five inches high, made of some material that will 40 not rust, and constructed in a manner to keep out water, all parts of the device being made or coated with material that will not rust. Within this box is located part of my device, consisting of an upright pivoted arm, A, having 45 the wing Y at its top and carrying the mutilated cog-wheel K near its lower end, and one or more electric solenoids, B B', or electromagnets, and a movable slide, C, having on its inner side the rack or teeth H and the dogs

R. The metallic bar C plays freely in openings through the solenoids, and is mounted on the anti-friction rolls G. The arm A has conical bearings at the bottom, and at the top of the box plays in the anti-friction rolls a. The solenoids and bar may be either round 55 or square.

Two flat springs, T T', Figs. 8 and 13, made of flat strips of brass, attached to a strip of some insulating material, and separated electrically, and this strip with the springs T T', 60 Fig. 13, fastened to the rim of the switch in such a manner that a metallic pin, E, Fig. 8, screwed into the arm F, is made to contact with the springs whenever the switch is 65 opened or shut.

A wire from the station battery (or other battery placed at any convenient point, or from a dynamo-current) is connected to the two inside ends, I, of the wires of the solenoids B B'. The other end of the battery connects 70 with the ground.

Two wires, O O', are connected with the flat springs T T' on the switch, and conducted to and connected with the outside ends of the wires of the solenoids Q Q', Fig. 4.

If the switch is to be opened, the arm F, Fig. 8, is raised to a horizontal position and moved to the left, facing and parallel to the track. As it is moved, the pin E comes in contact with the spring T', and, being connected 80 to the ground, completes the circuit through the solenoid B at the left, Fig. 1. The sliding bar C, however, is projecting as far to the left as it can go, and is not affected by the current, but remains stationary. The further 85 movement of lever F, however, brings it in contact with spring T and completes the circuit with the solenoid B' at the right, having passed beyond the spring T' and broken the circuit with solenoid B. As soon as the circuit is completed with solenoid B', it attracts the bar C and draws it along to the right on its bearings G until it projects beyond the end of solenoid B', as shown in dotted lines, Fig. 1. As the bar moves to the right, the 90 rack H on the bar operates the pinion K until the wing Y on post A stands at right angles to the track. The solenoid B' attracts the 95

bar H until a stop, M, on the wheel comes in contact with a lug, N, in the bottom of the box, Fig. 2, at which time the last tooth P' of the wheel K has passed the last tooth of the 5 rack and the dog R. The dog R is pivoted and held against the shoulder b by a spring, S, which allows the rack H to pass beyond the teeth in the wheel K, the dog R yielding to allow the teeth to pass, and then springing 10 back into position again.

The cut-away part U of bar C presses against the last tooth P' of the wheel and prevents the wheel turning back until the motion of the rack is reversed, when the dog R will 15 engage with tooth P' and turn the wheel in the opposite direction. In closing the switch the lever F is turned back again, breaking the circuit with spring T, bringing the pin E in connection with spring T' again, completing 20 the circuit with solenoid B again, which attracts the bar C and draws it to the left again, the rack H turning the pinion K, revolving the post A, and bringing the wing Y parallel with the track again.

25 On the tender of the locomotive or on any of the cars a connection is made with the air-pipe of the brakes, and a short pipe, c', attached, terminating in a valve, d', operated by a handle, Z, some twelve inches long, reaching 30 down far enough to come in contact with the wing Y on the arm A. When the switch is opened by the movement of handle F, as above described, and the circuit is completed, the solenoid B', through bar H, moves the wheel 35 K and post A so as to bring the wing Y at right angles to the track and in the path of the

handle Z. As the cars come along, the handle Z strikes the wing Y, opening the valve d' and allowing the air to escape from the air-pipe on the train, which, with the automatic brake, 40 sets the brake and stops the train. With the "straight air-brake" a connection is made with the air-drum in such a manner that the movement of the lever Z allows the air to pass into the air-pipe on the train, setting the 45 brakes.

The bar C, instead of operating the wing Y through the pinion Z, can be made to strike a lever at either end and move the wing Y into and out of position; or the bar itself may 50 be arranged to strike the arm or handle Z and operate the brakes.

What we claim as new is—

1. The combination, with a device on the cars for setting the air-brakes, of the wing Y, 55 rack H, and dogs R, operated automatically by the attraction of the solenoids, as and for the purpose set forth.
2. The rack H, the pivoted spring-dogs R, and the toothed wheel K, as and for the purpose set forth. 60
3. The rack H, the pivoted spring-dogs R, the bevel U on bar C, the toothed wheel K, the stop M, and the lugs N, as and for the purpose set forth. 65
4. The bar C, the rack H, the dogs R, and springs S, as and for the purpose set forth.

IVAN L. MELOON.

PHINEAS S. WHITING.
